COMBINATION STOVE AND SINK

Mike Tecton, 5101 45th St. NW,
Washington, D.C. 20016

Filed Sept. 3, 1965, Ser. No. 86,820

Term of patent 14 years

(Cl. D81—25)

FIG. 1

FIG. 2

FIG. 1 is a perspective view of a combination stove and sink, embodying my new design;

FIG. 2 is a top plan view thereof;

The underside of the combination stove and sink is substantially plain.

I claim:

The ornamental design for a combination stove and sink, substantially as shown and described.
